CONCRETE WALL CONSTRUCTION

Charles J. Ulrich, Royal Oak, Mich.

Application September 19, 1938, Serial No. 230,561

5 Claims. (Cl. 25—131)

My invention relates to building construction and its object is to improve and cheapen the construction of concrete buildings and the product thereof.

I accomplish this object as illustrated in the accompanying drawings in which:

Figure 1 is a sectional view—drawn to a relatively enlarged scale—of a portion of a wall of a building embodying my improvements, taken on or about line 1—1—1—1 of Figure 2, with the forms in place.

Figure 2 is a plan view showing a horizontal section taken through the empty forms.

Figure 3 is a perspective view, partly in section, showing a wall under construction, with the forms in place.

Figure 4 is a perspective view, partly broken away, of a tray such as described in my copending application Serial Number 168,981, filed October 14, 1937.

Figure 5 is a perspective view—partly in section—of the partially filled forms.

Figure 6 is a section—partly broken away—of the empty forms.

Figure 7 is a sectional view—partly broken away—of a building wall, constructed according to my invention.

Figure 8 is a detail view—in perspective—of one of the upright forms.

Referring now to the reference characters upon the drawings:

The numeral 2 denotes a wall footing. Parallel and adjacent to the inner edge of the footing 2, is secured an angle-iron 3, with one portion extending in a vertical plane. Numeral 4, indicates thin metal tubular uprights, rectangular in cross-section, closed at their inner faces and open at their outer faces. These uprights are secured at their lower ends, at intervals, to the upright flanges of the angle-iron 3,—see Figure 2. Each of these uprights consists of two members Z-shaped in cross-section, having outwardly extending flanges 4a, at their outer edges, and inwardly extending flanges 4b, at their inner edges,—see Figure 3.

The inner flanges 4b, are again turned inward at right-angles, to form the flanges 4c.

The two parts forming each of the uprights 4, are secured together by means of the flanges 4c. Numeral 5, denotes a wooden nailing strip clamped between the flanges 4c, having its inner surface flush with the inner edges of said flanges and extending into the hollow formed by the spaced walls of the uprights 4,—said latter portion being dove-tailed in cross-section. The

flanges 4c, and the nailing strip 5, are cut away at the lower end of the uprights 4, to accommodate the angle-iron 3, as shown in Figure 6.

Numeral 6, indicates strips of a "boarding material," which may be a Celotex insulating sheathing or the like, secured to and extending between the flanges 4a, of adjacent uprights 4, their edges registering with the inner edges of said flanges, leaving the outer faces of the uprights 4, unobstructed.

Numeral 3a, denotes an angle-iron extending along the upper edges of the "boarding material" 6, serving as an aligning and stiffening member.

Numeral 6a, are spacing lugs of bent sheet metal secured to the "boarding" 6, and extending outwardly as required, to determine the thickness of the wall to be cast. It will, however, be understood that while a relatively small number of the spacing lugs 6a, are shown in the several views of the drawings,—the number employed may be increased as required, to insure proper spacing of the trays,—hereafter more particularly described.

Numeral 7a, denotes reinforcing rods passing vertically through the interior of each of the uprights 4, and are supported by brackets 7, extending from the sides of the uprights.

Numeral 8, denotes metal strips, threaded at their inner ends upon the reinforcing rods 7a, and at their outer ends are provided with apertures,—for purposes hereafter described.

Numeral 9, denotes hollow trays, and 10,—see Figure 4, indicates sheets of coarse paper, which are thoroughly saturated with water, and placed in the bottom of the trays 9. Numeral 11 denotes a layer of moist plastic clay covering the surface of the outer sheet of paper 10.

Numeral 12, denotes a surface of aggregate or surfacing material, removably fixed in the plastic clay 11.

Numeral 13, denotes reinforcing rods extending upwardly from the footing 2,—then turning and extending horizontally through the space to be occupied by the wall 1. Numeral 14 indicates the floor beams.

The web closing the inner surfaces of the uprights 4 is cut away at the top, at 4d, as indicated most distinctly in Figure 8, to admit the ends of the floor beams 14,—which extend a distance into the uprights 4, as indicated in Figure 6.

The edges of the trays are preferably turned over as indicated at 9a.

In constructing a wall,—the trays partly filled as above described are placed end to end with their open face inward in position to form the

outer wall of the form or mold, their edges engaging against the outer ends of the lugs 6a, to position them relative to the surface of the boarding 6, and the edges of the upper trays resting upon those of the lower trays. The strips 8 extend between and beyond the edges of the superimposed trays as shown in Figure 1. A strut 15, having engaging rods 15a, extending from its ends is placed between two vertically disposed strips 8 with its rods 15a, engaging in the apertures in the outer ends of said strips, and a channel iron 16, is then placed between the strut 15 and the trays 9. A bolt 17 at the center of the strut 15, is then screwed up against the channel iron 16, forcing the same inward and pressing the tray firmly into position.

When the outer wall of the form or mold is thus formed the concrete is poured in the space between the trays and the boarding 6, and flows into the tray against the surfacing material 12 therein, and into the uprights 4, and around the ends of the floor beams 14. When the concrete has set the trays are removed, the wall has its outer surface marked by grooves 9a, formed by the edges of the trays, giving the appearance of cut stone,—see Figure 5. The concrete will bind the surfacing material firmly to itself and the clay can be washed off leaving the surfacing material exposed to view. The concrete in the uprights 4, forms supporting studs integral with the walls and the ends of the joists, or floor beams and are firmly embedded in the concrete wall construction. The boards for the wall of the enclosure may be nailed to the strips as indicated at 18, in Figure 3.

What I claim is:

1. In an apparatus of the kind described, a plurality of vertical tubular uprights, closed at their inner faces and open at their outer faces; means secured to the lower ends of the uprights adapted for the attachment of the uprights to a wall footing; sheathing secured to the uprights, closing the space between the uprights; binding strips, adapted to be secured at their inner ends to vertical reinforcing rods supported by the uprights, a plurality of wall surface molding sections, said binding strips extending outwardly between and supporting said wall surface molding sections, supported by the binding strips; and clamping means, secured to the outer projecting ends of the binding strips, adapted to clamp the wall surface molding sections in position.

2. In an apparatus of the kind described, a plurality of vertical tubular uprights, closed at their inner faces and open at their outer faces; means secured to the lower ends of the uprights, adapted for attaching the uprights to a wall footing; sheathing secured to the uprights, closing the space between said uprights; outwardly extending spacing members carried by the sheathing, a plurality of wall surface molding sections aligned in spaced relation to said sheathing by the spacing members; binding strips, adapted to be secured at their inner ends to ver-

tical reinforcing rods supported within the tubular uprights, said binding strips extending outwardly between and supporting the wall surface molding sections, and clamping means, secured to the outer projecting ends of the binding strips, adapted to clamp the wall surface molding sections in position against the spacing members.

3. In an apparatus of the kind described, vertical spaced tubular uprights adapted to be secured by supporting means upon a wall footing; 10 a sheathing secured to the uprights, closing the space between the uprights; a plurality of wall surface molding sections, comprising hollow trays adapted to receive and support a plastic clay and aggregate coating for a concrete wall; means for maintaining said wall surface molding sections in fixed spaced relation to said sheathing; and adjustable clamping means, clamping said wall surface molding sections against the means for maintaining said wall surface molding sections in fixed spaced relation to the sheathing, to receive a concrete wall mixture.

4. In an apparatus of the kind described, the combination of vertically arranged flanged Z bars disposed in pairs with a space between the flanges for clamping a nailing strip therein, a sheathing between the pairs of uprights and secured thereto; outwardly extending spacing members carried by the sheathing; means for supporting vertical reinforcing rods carried by the Z bars; a plurality of wall surface molding sections, binding strips, adapted to be secured at their inner ends to the reinforcing rods, and extending outwardly between and supporting the wall surface molding sections, and adjustable clamping means between the binding strips, and secured thereto, comprising a bar, provided with a screw passing therethrough and engaging a channel iron, adapted to clamp the wall surface molding sections against the ends of the spacing members.

5. In an apparatus of the kind described, the combination with means adapted to support vertically spaced uprights upon a wall footing; vertically spaced uprights; suitable sheathing secured to the uprights closing the space between the same; means for supporting a plurality of vertically disposed reinforcing rods within the uprights; a plurality of wall surface molding sections, comprising hollow trays, adapted to receive and support plastic clay and aggregate coating, for a concrete wall; means comprising a plurality of metal binding strips adapted to be connected with the reinforcing rods, and extending outwardly between the wall surface molding sections,—the sheathing,—and the spaced uprights; means for maintaining said wall surface molding sections in spaced relation to said sheathing; adjustable clamping means, engaged to the binding strips, adapted to clamp the wall surface molding sections against the means for maintaining said wall surface molding sections in spaced relation to the sheathing to receive plastic concrete.

CHARLES J. ULRICH.
